(57) **CLAIM**

The ornamental design for a tire, as shown and described.

DESCRIPTION

FIG. 1 is a front elevation view of a tire showing our new design, the rear elevation view being identical thereto;
FIG. 2 is a right side elevation view thereof;
FIG. 3 is a left side elevation view thereof;
FIG. 4 is a front, right perspective view thereof; and,
FIG. 5 is an enlarged partial front elevation view thereof.
The short-dash broken line showing is for the purpose of
illustrating unclaimed portions of the tire and forms no part
of the claimed design.
